US0D1029913S

(12) **United States Design Patent** (10) **Patent No.:** **US D1,029,913 S**
(45) **Date of Patent:** **** Jun. 4, 2024**

(54) **BINOCULAR CAMERA**

(71) Applicant: **Hangzhou Jiefeng Technology Co., Ltd**, Hangzhou (CN)

(72) Inventor: **Liangfeng Lei**, Hengyang (CN)

(73) Assignee: **HANGZHOU JIEFENG TECHNOLOGY CO., LTD**, Hangzhou (CN)

(**) Term: **15 Years**

(21) Appl. No.: **29/838,237**

(22) Filed: **May 11, 2022**

(30) **Foreign Application Priority Data**

Mar. 18, 2022 (CN) 202230141627.4

(51) **LOC (14) Cl.** **16-01**

(52) **U.S. Cl.**

USPC **D16/210**; D16/200

(58) **Field of Classification Search**

USPC D16/200–203, 207–208, 213–214, D16/218–219, 210; D10/46, 61, 104.1, D10/106.6, 106.7, 109.2; D14/203.1,

(57) **CLAIM**

The ornamental design for a binocular camera, as shown and described.

DESCRIPTION

FIG. 1 is a perspective view of a binocular camera showing my new design;

FIG. 2 is another perspective view thereof;

FIG. 3 is a front view thereof;

FIG. 4 is a back view thereof;

FIG. 5 is a left side view thereof;

FIG. 6 is a right side view thereof;

FIG. 7 is a top view thereof; and,

FIG. 8 is a bottom view thereof.

The broken lines represent the portions of the design that form no part of the claim.

1 Claim, 8 Drawing Sheets
